UNITED STATES PATENT OFFICE.

HERBERT PEARCE, OF STRETFORD, ENGLAND, ASSIGNOR TO WESTINGHOUSE ELECTRIC & MANUFACTURING COMPANY, A CORPORATION OF PENNSYLVANIA.

DISTRIBUTING SYSTEM.

Application filed May 22, 1920. Serial No. 383,368.

To all whom it may concern:

Be it known that I, HERBERT PEARCE, a subject of the King of Great Britain, and a resident of Stretford, in the county of Lancaster, England, have invented a new and useful Improvement in Distributing Systems, of which the following is a specification.

My invention relates to protective gear for alternating electric current systems and particularly to apparatus of this kind designed to protect a system not only when faults arise but, also, on the occasion of a fault to ground of one or more of the conductors.

One object of my invention is to provide a system of protection for an electric distributing system comprising means that may be adjusted to operate at a relatively large value of current to protect the system against excessive currents arising from short circuit or unbalance conditions and means that may be adjusted to operate at a relatively small value of current to protect the system from aggravation of ground conditions.

Another object of my invention is to provide a system of the above-indicated character that may be applied to protect parallel-connected feeder circuits or translating apparatus, such as dynamo-electric machines or transformers.

In apparatus of this kind, as is well known, relay devices are commonly employed that are connected with the secondaries of series transformers in the various conductors of the system, said relays controlling the operation of circuit breakers for cutting out a conductor or piece of apparatus, such as a transformer or generator, in the system when necessity arises. Many arrangements have been devised in which the same relays are utilized for protecting the system against faults between conductors and faults to ground. Such arrangements may cause inconvenience due to the fact that the use of a sensitive relay is not always permissible in dealing with faults between conductors as it is liable to be actuated on the occasion of an overload and

also may be actuated when one conductor is switched into circuit before another conductor. On the other hand, in order to protect the system in case of earth leakage, the relay should be as sensitive as possible.

In view of the above conditions and in order to avoid the disadvantages referred to, I provide, in addition to relays that protect against faults between conductors, a relay that may be more sensitive and that operates only in the event of a fault arising which involves leakage to earth.

In order that the nature of the invention may be more clearly understood, it will now be described with reference to the accompanying drawings which are diagrammatic views of various systems embodying my invention.

Figures 1, 2, 3 and 4 are diagrammatic views of electrical circuits illustrating the operation of the protective system embodying my invention upon the occurrence of faults of different types at different points in the system;

Fig. 5 is a schematic view of a relay embodying my invention that may be employed in the protective system disclosed herein;

Fig. 6 is a diagrammatic view of an electrical circuit, illustrating the connection of the operating coils of the relay in Fig. 5 to the systems illustrated in Figs. 1 to 4, inclusive;

Figs. 7, 8 and 9 are diagrammatic views of single-phase and two-phase circuits, illustrating the application thereto of the protective system embodying my invention;

Fig. 10 is a diagrammatic view of an electrical circuit in which the protective system is applied to protect the windings of a dynamo electric machine;

Fig. 11 is a diagrammatic view of an electrical system in which the protective arrangement is applied to both ends of parallel-connected transmission circuits, and

Fig. 12 is a diagrammatic view of an electrical circuit, illustrating the application of my protective system thereto.

Figure 1 is a diagrammatic view of a three-phase system having two sets of feeder conductors 1, 2, 3 and 4, 5, 6 in parallel

relation for connecting a supply circuit 7 to a set of bus-bar conductors 8 or other circuit in which energy is to be utilized. Series transformers with secondary windings 9, 10, 11 and 12, 13, 14 are provided near each end of both sets of the feeder conductors, one terminal of the three secondary windings of the transformers in each set of feeder conductors being connected together at 15 and 16 to form a neutral point. The other terminal of each of the secondary windings 9, 10, 11 is respectively connected to the free terminals of the secondaries 12, 13, 14 of the conductor of the corresponding phase in the second set of feeder conductors and the connecting conductors 17, 18, 19 are each joined to one terminal of the relays 20, 21, 22. There are thus three relays, one corresponding to the conductor of each phase. The free terminals of the relays 20, 21, 22 are joined together at 23 and connected through a fourth relay 24 to the two neutral points 15, 16 of the six secondary windings 9, 10, 11, 12, 13, 14 by the conductors 25, 26. The secondary windings corresponding to the two feeder conductors of any one phase are so connected that the relays 20, 21, 22 will be traversed by currents of a value depending upon the difference between the currents traversing the respective secondary windings 9 and 12, 10 and 13, 11 and 14, to which they are connected.

Fig. 2 illustrates the course of the currents (shown by the arrows) in the relay circuits, set up by an earth fault at X, for example, external to the feeder circuits 1, 2, 3 and 4, 5, 6 and approximately equi-distant from the two sets of transformer windings 9, 10, 11 and 12, 13, 14, so that the latter are traversed by equal earth currents. The current will traverse the path 9, 17, 12, 26, 25 and no current will traverse any of the relays. It is understood that the arrows refer only to that portion of the current that is set up by the leakage current and that the load currents are not indicated.

If the fault were so located that unequal currents would flow in the secondary windings of the transformers, a current would flow through the relay 24 as well as through one or more of the relays 20, 21, 22. For example, Fig. 3 illustrates the course of the currents in the case of an earth fault on the phase conductor 4 at Y. As regards the equipment which is located at the substation end of a pair of parallel feeder conductors, it will be seen from the drawing that, in this case, the current reverses in the secondary winding 12 and traverses both the relays 20 and 24.

Fig. 4 shows the path traversed by the currents in the case of a fault between two phases 1 and 2 of the feeder conductors when no leakage to earth is involved, as

shown by the dotted line Z, for example. In this case, the current traverses the winding 9, the relays 20 and 21, and the winding 10, and similarly the winding 12, the relays 20 and 21, and the winding 13, but no current traverses the relay 24.

It will be seen from the above whereas currents traverse one or more of the relays 20, 21, 22, when unbalancing occurs due to any kind of fault, current will only traverse the relay 24 when an unbalanced fault to earth occurs as shown, for example, in Fig. 3. Consequently, the relays 20, 21, 22 can be so made or adjusted with coarse setting that they will only operate when the out-of-balance current flowing in the feeder conductors is greater than a predetermined amount which may be, for example, the normal current flowing in the feeder conductor when it is fully loaded. By this means, operation of the relays is avoided, in case one feeder conductor is switched into circuit before the other. The relay 24, however, may be made very sensitive as it is not operated by the out-of-balance current that is effected by faults between conductors, but only when an earth leakage occurs.

It will be clear from what has been said above that no difficulty is experienced when only one of the two feeder conductors is connected into circuit, and in such cases the feeder conductor is provided with simple overload protection by means of the three relays 20, 21 and 22 and simple leakage protection by the fourth relay 24. The overload relays 20, 21, 22 may be provided with a time limit device so constructed that the delay might be adjusted to zero when the relays perform their normal function of protecting against faults between phases when both feeder conductors are in circuit, or, a time delay device may be provided when it is necessary to operate for any length of time with a single feeder conductor connected. The latter condition, however, is a special one and, in normal operation, the time delay would not be required even when the feeder conductors were being switched into, and out of, circuit.

As the fourth, or leakage, relay 24 protects the system against faults to ground, it will be clear that one of the three first mentioned or overload relays 20, 21, 22 may be omitted, without inconvenience, if desired.

The series transformers cannot, as is well known, be so constructed that they will be balanced at all conditions of load, that is to say, they may balance closely when normal currents traverse their respective conductors and may be considerably out-of-balance when a short-circuit current obtains. If necessary, resistances or reactances may be provided in series with any

transformer, conductor or relay, to improve the balance under short-circuit conditions, but it is preferable, however, to construct the relays with biasing coils that are connected in the secondary windings of the transformers.

With a three-phase system there may be three biasing windings on each relay, thus forming a polyphase restraining magnet that produces much less vibration and chattering of the relay armature than is set up by single-phase biasing coils such as have previously been used for this purpose. A preferred construction of such a relay is illustrated in Fig. 5. An operating coil 27 is wound on a magnet 28 that is arranged to attract a relay armature 29 which is partially balanced by a counterweight 30, and is provided with an auxiliary armature 31, at right angles to the first, that is attracted by the three-phase magnet 32 which is provided with plurality of coils 33, 34, 35. These coils may be so connected in the secondary circuits of the respective transformers, as shown in Fig. 6, that they may be traversed by currents proportional to the load currents. The leakage relay may, therefore, be provided with a restraint or bias that depends upon the current that traverses the feeder conductors. The relay may thus be very sensitive to earth leakage currents, at normal load, but will have its sensitiveness reduced when the feeder conductors are traversed by short-circuit currents.

In some cases it may prove sufficient to provide restraining coils on the relays that are connected to two of the phases only.

A relay constructed in this manner may be used on single feeders in which case the four relays will be connected in circuit with the secondaries of three transformers only.

Fig. 7 shows how the invention may be applied to a single-phase system having two sets of feeder-conductors connected in parallel relation. At each end of the feeder conductors, four series transformers are provided with their secondary windings 9, 10 and 12, 13, connected in a closed circuit and equi-potential points of this circuit are connected, in a well-known manner, through a relay 20 corresponding to the overload relays hereinbefore mentioned. The common terminals of the secondary windings 9, 10 and 12, 13 that are also equi-potential points, under normal conditions, are connected together by the conductor 25, 26, that is connected to one of the first-mentioned equipotential points through another relay 24. This relay corresponds to the leakage relay 24 shown in Figs. 1 to 4. The restraining or biasing magnet 33 of the relay, that is in series with the transformer secondary windings, will be a single-phase

magnet although it may be provided with a shaded pole or any equivalent phase-splitting device.

In Fig. 8, the invention is shown as applied to a two-phase four-wire system of distribution. This necessitates the addition of transformers for the fourth wire. The secondary windings are indicated at 11^a and 14^a, respectively, with a second restraining coil 35^a included in the circuit and a second overload relay 22^a.

Fig. 9 shows the invention as applied to a two-phase three-wire system. The arrangements in this case are similar to those shown in Fig. 1 but the ratio of the transformers in the common phase conductors of each feeder conductor must be proportioned to suit the additional current that traverses these conductors. The operation of the arrangements shown in Figs. 8 and 9 will be readily understood, by those skilled in the art, without further description, as it is substantially the same as already described with reference to Figs. 1 to 4 of the drawings.

The employment of an extra relay for dealing with earth leakage, as hereinabove described, may be applied to the protection of transformers in which a set of series transformers, that are connected on the primary side of the transformer that is to be protected, have their secondary windings balanced against corresponding secondary windings of a set of series transformers that are connected on the secondary side of the transformer that is to be protected. Heretofore, it has been usual in such protective systems to employ relays having a coarse setting or a considerable time limit, or both of these characteristics in order that the relays might not be operated by the out-of-balance current that obtained when one side of the transformer was switched into circuit before the other side. With the usual arrangement the relays have the same setting for earth leakage faults as they have for faults between conductors, which, as before mentioned, is undesirable.

If the construction of relays with biasing coils, as herein indicated, is adopted, the earth leakage relay may be made very sensitive and the overload relays less sensitive to obtain the advantages pointed out above.

In Fig. 10, the arrangement is shown as applied to the protection of a three-phase generator in which an earthing resistance is connected to the neutral point 36 of the system. The generator windings 37, 38, 39 are connected through a circuit interrupter 40 to the bus-bars 41. Series transformers are provided in the phase conductors between the generator terminals 37, 38, 39 and the bus-bars 41, and in the phase conductors

between the generator windings 37, 38, 39 and the neutral point 36, the secondary windings of the transformers 9, 10, 11, 12, 13, 14 being connected with overload relays 21 and 22 and a leakage relay 24. The operation of this arrangement of relays is similar to that of the arrangement shown in Fig. 1 and will be understood without further description.

10 The following advantages are obtained, namely: The protection against earth faults is more sensitive than with the usual arrangement of relays; a smaller earthing resistance is required; and the transformers 15 that are employed in the protective gear need not be constructed to balance so accurately. In addition to these advantages a greater portion of the generator winding may be protected. This will be clear 20 from the following considerations. If an earthing resistor that is connected to the neutral point of a three-phase generator is designed to permit the traversal of a current of predetermined value when one phase 25 terminal is connected to earth, only half that current will flow if the mid-point of a phase winding is connected to earth, and similarly for other portions of the winding, the maximum earth current which may flow 30 at normal voltage depends upon the particular portion of the winding that is earthed. Consequently, if a relay operates at a value corresponding to fifty per cent of the maximum current that may traverse 35 the earthing resistance, then only half of the generator winding will be protected, but if the relay is made sufficiently sensitive, as it can be with the arrangement shown, to operate at a value corresponding to five 40 per cent of the maximum current, then ninety-five per cent of the winding is protected against earth faults.

In the arrangement shown in Fig. 1 where the invention is applied to the protection of 45 one end of a pair of parallel feeders, in the event of a fault occurring on either feeder, both feeders will be cut out of circuit and the supply may thus be entirely interrupted. In order to avoid this occurrence, the fourth 50 relay 24, hereinbefore termed the leakage relay, may advantageously take the form of the well known wattmeter type of relay. As shown in Fig. 11, the current coil 24 of the relay is connected in circuit with the 55 secondary windings 9, 10, 11 and 12, 13, 14 of the protective transformers, and the potential coil 42 is connected between ground and the star, or neutral, point of any convenient generator, transformer or similar 60 apparatus. In the upper part of Fig. 11, for example, that is, in the arrangement applied at the generator end of the feeders, the potential coil 42 is shown connected to the 65 secondary winding 43 of a potential transformer, the primary winding 44 of

which is connected across a limiting resistor 45 connected between the ground and the neutral of a three-phase star-connected generator 46 feeding bus-bars 41. In the lower part of the figure, at the substation 70 end of the feeders, the primary winding 47 of the potential transformer is shown connected between the ground and the neutral point of a star wound transformer or reactance 48 connected to the substation bus-bars 49.

In operation, if an earth occurs on the third phase 6 of the second feeder, the transformer winding 14 will be traversed by a current of greater value than transformer 80 11 and a current of a value that is the difference between the values of these currents will traverse the relay winding 24. At the same time, the traversal of leakage current to ground creates a potential across the resistance 45 that induces a potential in the secondary winding 43 of the potential transformer and thus energizes the potential winding 42 of the leakage relay 24.

The primary leakage current is set up by 90 the third phase of the generator, and for the purpose of this invention this phase winding may be regarded as a single-phase generator producing a current equal to the leakage current at a voltage equal to the 95 potential drop across the resistance 45. This current and potential will be more or less of the same phase according to the relative amount of resistance and reactance which the current must traverse. Consequently, a 100 wattmeter relay provided with a current winding 24 and a potential winding 42 may be so provided with two sets of contacts that if the current in the winding 14 is greater than that in the winding 11 the second 105 feeder interrupter will be opened, and, correspondingly, if the current in the winding 11 is greater than the current in the winding 14, the interrupter in the first feeder will 110 be opened.

With the arrangement in Fig. 11, the phase relays 21 and 22 are required to operate both interrupters simultaneously, whereas the wattmeter relay is required to open either the one switch or the other according 115 to which is the faulty circuit. This is arranged by fitting each oil switch with two trip coils, one for use with the phase relays 21 and 22 and one for use with the wattmeter leakage relay 24. Alternatively, the 120 same result could be obtained by duplicating the relays instead of the trip coils.

The potential transformer 43, 44 or 48, 125 is employed in order to reduce the voltage on the potential coil of the wattmeter relay to a safe value. If the relays are situated in a power house where an earthing resistor is provided, the potential transformer may conveniently be connected across the terminals of such resistor.

The wattmeter relay, if desired, may be provided with a polyphase restraining or biasing magnet similar to that hereinbefore described with reference to the ordinary 5 relays.

In Fig. 12, the invention is shown as applied to the protection of a single feeder circuit. In this case the overload relays 20, 21, 22 at the two ends of the feeder to be 10 protected are respectively connected in series by pilot wires 50, 51, 52 and the secondary windings 9, 10, 11, and 12, 13, 14 of the series transformers of each phase are also 15 respectively connected in series to oppose each other under normal conditions. The restraining or biasing windings 33, 34, 35 at each end of the feeder are connected between the respective pilot wires and the neutral point of the secondary circuits through the 20 leakage relays 24 and the high voltages that are induced across the protective transformers when the feeder conductors are traversed by heavy short-circuit currents are utilized to energize the restraining windings 33, 34, 35 so that very sensitive leakage 25 relays may be employed.

I do not limit my invention to the specific arrangements illustrated, as various modifications may be made therein within the 30 spirit and scope of the invention as set forth in the appended claims.

I claim as my invention:

1. In an electric distributing system, the combination with a translating apparatus, 35 of means responsive to the current traversing the windings of the translating apparatus at one end thereof and responsive to the current traversing the windings at the other end of the apparatus, electro-responsive means adjusted to operate when a 40 relatively large value of current entirely traverses the apparatus, and means adjusted to operate when a relatively small value of current traverses a portion of the windings 45 of the apparatus.

2. A protective system for a polyphase translating apparatus provided with a plurality of windings, comprising current 50 transformers disposed at the terminals of the windings, auxiliary circuit conductors connecting corresponding transformers and electro-responsive devices connected between the auxiliary conductors, one of said devices being adjusted to operate when a 55 relatively large value of current traverses the corresponding winding of the apparatus and another of said devices being adjusted to operate when a relatively small value of current traverses a portion of a winding of 60 the apparatus.

3. In a power-distribution system, the combination with two sets of conductors and current transformers therefor, of an auxiliary circuit for connecting corresponding 65 current transformers and normally de-

energized means connected across said auxiliary circuit to be energized upon the occurrence of abnormal conditions in either set of conductors, one of such means being adjusted to operate at a relatively low value 70 of current caused to traverse a conductor by reason of a ground thereon.

4. In combination, a source of energy comprising a plurality of windings, two sets of conductors connected thereto, current 75 transformers for the respective sets of conductors, auxiliary circuit conductors for connecting corresponding current transformers of both sets of conductors, means connected between the auxiliary conductors 80 to respond to currents resulting from predetermined faults on a conductor of one set, and means associated with the former means to respond to a current resulting from a 85 ground on a conductor of one set of conductors or on one of the windings.

5. The combination with a polyphase apparatus provided with a plurality of windings, the neutral point of which is grounded, 90 of a plurality of current transformers connected between the neutral point and one set of terminals of the windings and a plurality of transformers between the other terminals of the windings and an external circuit, auxiliary conductors for connecting corresponding transformers in circuit and means operatively connected in circuit with such auxiliary conductors to indicate the occurrence of a ground upon a winding of 95 the apparatus and upon the occurrence of any fault on the conductors beyond the terminals of the windings.

6. The combination with two sets of conductors adapted to be traversed by currents bearing predetermined ratios, of current 100 transformers in circuit therewith, auxiliary circuits connecting the transformers and electro-responsive means connected in circuit with the auxiliary circuits and operative upon the occurrence of both faults 110 to ground and faults between conductors.

7. The combination with two sets of conductors adapted to be traversed by currents bearing predetermined ratios, of current 115 transformers in circuit therewith, auxiliary circuits connecting the transformers and electro-responsive means connected in circuit with the auxiliary circuits comprising means responsive to a variation from the predetermined ratios of the current and 120 means responsive to a ground fault on a conductor.

8. The combination with two sets of conductors adapted to be traversed by currents bearing predetermined ratios, of current 125 transformers in circuit therewith, auxiliary circuits connecting the transformers and electro-responsive means connected in circuit with the auxiliary circuits comprising means adjusted to operate at a relatively 130

- large value of current in response to an abnormal variation from the ratio to be preserved between the currents traversing the two sets of conductors and means adjusted to operate at a relatively small value of ground current.
9. The combination with a dynamo-electric machine provided with a plurality of windings, of current transformers disposed between the terminals of the windings and external conductors to be connected to the windings, auxiliary conductors for connecting the transformers in circuit, means adjusted to operate upon the occurrence of predetermined conditions normally manifested by currents of excessive value and means adjusted to operate upon the occurrence of predetermined conditions normally manifested by currents of relatively small value.
10. In combination, an alternating-current circuit, current transformers disposed at predetermined positions thereof, connecting conductors between the transformers, and a relay connected to the conductors and comprising means actuated when a ground current traverses the circuit if not more than normal circuit current traverses the circuit.
11. In an electric circuit, the combination with a plurality of current transformers and connecting conductors therefor, of means responsive to a ground current, and means for controlling the responsiveness thereof in accordance with the value of the circuit current.
12. In combination, an alternating-current circuit, current transformers at each end thereof, relays associated with the current transformers, means for connecting the relays in circuit with the transformers, means energized upon the occurrence of a ground on the circuit to be actuated to perform a predetermined operation and means for controlling such actuation in accordance with the degree of balance between the currents traversing both ends of the circuit.
13. The combination with an alternating current electrical circuit, of a protective device therefor comprising a plurality of star-connected current transformer groups associated with at least two points in said electrical circuit, the neutral points of said transformer groups being electrically connected, other terminals of co-operating transformers in each of said groups being electrically connected, a plurality of star-connected relays respectively in circuit with the said transformers and a ground relay in circuit with the neutral point of said relay connection and the neutral point of said transformer groups.
- In testimony whereof, I have hereunto subscribed my name this first day of May, 1920.

HERBERT PEARCE.
